UNITED STATES PATENT OFFICE.

PAUL STONER, OF WAYNESBORO, PENNSYLVANIA, ASSIGNOR TO LANDIS TOOL COMPANY, OF WAYNESBORO, PENNSYLVANIA, A CORPORATION OF PENNSYLVANIA.

RECIPROCATING GEARING FOR GRINDING-WHEEL CARRIAGES.

Application filed November 18, 1920. Serial No. 424,899.

To all whom it may concern:

Be it known that I, PAUL STONER, a citizen of the United States, residing at Waynesboro, in the county of Franklin and State of Pennsylvania, have invented certain new and useful Improvements in Reciprocating Gearing for Grinding-Wheel Carriages, of which the following is a specification.

10 My said invention relates to a reversing gearing intended primarily for use in driving grinding wheel carriages reciprocatingly, but adapted for use either in whole or in part in machines of widely-varying types, either for reversing clutches or for other purposes. One object thereof is to provide a device in which a single lever may act as means for stopping and starting the reciprocation of the carriage and also as a reversing means having connected thereto adjustable devices to determine the length of stroke for the carriage.

25 Another object of the invention is to provide manual means for positioning the carriage while the power is off.

A further object is to provide means to stop the carriage by holding the reversing clutch in inactive position.

Referring to the accompanying drawings 30 which are made a part hereof and on which similar reference characters indicate similar parts,

Figure 1 is a top plan view of my device,

Figure 2, a vertical longitudinal section 35 of the same on line 2x2 of Figure 1;

Figure 3, a vertical section on the line 3x3 of Figure 2, showing the operating lever and its associated parts;

Figure 4, a detail horizontal view on the 40 line 4x4 of Figure 3 showing the clutch centering device; and

Figure 5, a section on line 5—5 of Figure 1, clearly shows the reversing clutch and related parts.

45 In the drawings, A represents the frame of a grinding machine, on which is mounted a reciprocating carriage B, shown fragmentarily in Figure 2. Shaft 10 journaled in a gear casing 11 constitutes the power shaft for the carriage and drives a shaft 14 through gears 12 and 13. Through gears 16 and 17 shaft 14 drives a parallel shaft 15 at a speed uniform with its own. Gear 17 is elongated to form driving means 50 for a gear 21 loose on shaft 20, while shaft

14 through gear 18 drives gear 19, also on shaft 20, in the reverse direction to gear 21.

A clutch sleeve 24 having teeth at each end is splined to shaft 20. The teeth at the ends of the clutch sleeve are adapted 60 to engage similar teeth on gears 19 and 21, thus forming a reversing clutch to drive the shaft in opposite directions according to the position of the clutch sleeve. At one end of the shaft is a bevel pinion 22 meshing with a bevel gear 23 on a shaft 25, which also carries a pinion 26 driving a gear 27 on a shaft 28. This shaft is connected through a tarry device to a driven gear 29 meshing with a rack 30 on the 70 grinding wheel carriage B, and through these connections the reversing shaft 20 acts to drive the carriage to and fro.

The reversing clutch sleeve 24 is operated by a lever 31 in the form of a frame surrounding shaft 20 and connected to the clutch sleeve by rollers 32 (Fig. 2), mounted on the lever. The clutch lever is journaled at one side on a sleeve 33 fitted in an opening of frame A and fastened therein 75 by means of screws. At the other side of the shaft it is journaled on a sleeve 79 hereinafter described. It has a downward extension 34 engaging between ears on an actuator 35 to be later described, and also 80 carries an annulus 36 on a vertical pivot said annulus being held from rotation by a pin 36'. A winged shifter 37 on a fixed pivot 38 forms a second actuator for the clutch lever.

Adjacent to the shaft 28 which drives the wheel carriage is a shaft 39 connected to the former by gears 40, 76 and 41. A sleeve 42 pinned to shaft 39 forms one member of a clutch, teeth at its end being adapted to engage corresponding teeth on a clutch sleeve 42' and both sleeves being journaled in a bearing 43. At one end the sleeve 42' has flanges 44 and 45 forming a groove for engagement by a clutch shifter. The flange 45 has notches formed therein. A detent 46, slidably mounted in an extension 47 on a sleeve 48 engages one of the notches when the clutch member 42 is in inactive position to hold this member stationary, as well as a shaft 49 to which it is splined and the hand wheel 50 all of which have a tendency to rotate due to the friction of a rotary sleeve 79 surrounding the shaft. When the clutch members 42, 100

105

110

42' are in engagement the hand wheel forms manual means to move the grinding wheel carriage.

The clutch member 42' is controlled by a 5 yoke 51 pivoted at 52 on sleeve 48 and straddling shaft 49. This yoke is connected to lever 35 by a yieldable coupling consisting of a yoke 53 secured to lever 35, a yoke 54 secured to yoke 51, and a link 55 having 10 a pin and slot connection with yoke 53 and a head engaging under the arch of yoke 54 whereby it may have movement relative to both yokes.

A spring 56 surrounds link 55 and tends 15 to force the yokes apart. Each yoke carries a collar pivoted between its bows and these collars are held by screws 57 and 58 respectively to lever 35 and clutch-yoke 51.

The lever 35 straddles shaft 49 and is pivoted at 59 below the shaft on a hub 60 free to oscillate on the fixed bearing sleeve 33 surrounding spindle 79 and extending at its under side from the nut 85 to a shoulder on sleeve 33. The lower extensions 35' of lever 20 35 are affixed to pivot 59 by pins 59' (Figure 3). A detent 61 slides in a recess in lever 35, being forced downward by a spring 63 whose ends rest in cored out portions of screw 57 and plunger 61, respectively. The detent is 25 prevented from rotating by a pin and slot connection at 62 and has an oppositely beveled end portion engaging an oppositely beveled holding member 64 removably mounted in the upper part of sleeve 60. The 30 movement of lever 35 inward and outward on the machine is limited in one direction by engagement at two points with member 37, and in the other by engagement of a face 97 on the lever with a shoulder 98 on the hub 60.

The portion of lever 35 adjacent the holding device 64 is shaped as indicated in Figure 4 with opposed projecting edges 65 and 67 to engage the wings 66 and 68 of winged member 37, and bring said member to the central position indicated in Figure 4, from the extreme position of Figure 1 or from the opposite extreme. The position of member 37 is determined by the reversing clutch 45 through shifter 31, roller 36, and projections 69 and 70 embracing the roller, consequently lever 35 can move the clutch lever to central position by its action on member 37.

A downwardly extending yoke 71 integral 55 with oscillatory hub 60 or fixed thereto carries pivot pin 59 (Fig. 2) and has adjustable screw-studs 72, 72 for engagement with the lower arm 34 of the shifter for the reversing clutch. It also carries a roller 73 at 60 its lower end engaging a yieldable detent 74 having oppositely inclined faces tending to move the lever to one or the other extreme position and hold it there. The spring of 65 the detent is held in place by a screw plug 74'.

Underneath the shaft 39 is a shaft 75 driven through meshing gears 41 and 76, and this shaft through gears 77 and 78 drives a hollow spindle 79 surrounding shaft 49. This sleeve has a toothed portion at 80, 70 whose teeth engage with those of an internal gear 81 constituting a dog-wheel for lever 35. This gear is held between a flange A' of frame A, and a face plate 82 fitting within a flange 86 of the gear and sleeved on a bearing 83 in which shaft 75 is also journaled. The face plate is held in position by a nut 84 on sleeve 83, and by hub 60 engaging an opening in the plate, the hub 60 preventing 80 rotation of the face plate and being itself held in place by a nut 85 on rotary spindle 79.

Flanges 86 hold the dog-wheel 81 in operative relation to teeth 80 and it has a circumferential groove 87 in its face in which are adjustably mounted dogs 88 and 89 having worms 90 and 91 meshing with teeth 92 on dog-wheel 81. The dogs are adapted to strike alternately against the projecting portion of a plunger 93 on lever 35, for reversing the machine and they are adjusted as shown by turning worms 90 and 91 to vary the length of stroke of the machine. A spring forces the plunger downward, and it may be withdrawn, as when the carriage is 95 to move past a dog 88 or 89, by drawing the cap 94 upward and turning it to bring the reversed portion of slot 95 into position so that the pin 96 may hold the plunger up.

In operation the carriage is normally 100 driven to and fro by the shaft 10 and the train of gearing to rack 30, the dog-wheel acting to throw lever 35 first to one side, as in Fig. 3, and then to the other side, by alternately engaging opposite sides of plunger 105 93. After the lever is moved far enough to cause roller 73 to pass the crest of detent 74, this detent will act to throw the lever quickly, but yieldingly to the other extreme position, so insuring proper engagement of the 110 reversing clutch.

When the operator desires to stop the carriage he moves the lever 35 in the direction of the arrow, (Fig. 2). Detent 61 rides up one side of the holding device 64 and down the other to hold the lever in place. As the lever moves over, e. g., from the position of Figure 3 toward the carriage, its edge 65 will strike wing 66, which at this time is in its extreme right-hand position, as 115 shown in Fig. 1. Lever 35 now swings member 37 toward central position and this member by its projection 70 moves clutch lever 31 toward neutral position for sleeve 24. As the lever rides along face 66 this face has also a tendency to cam the lever toward central position, and which ever one of levers 35 and 31 happens to be in the lead will also 120 act on the other below the shaft where screws 72 are in position to engage arm 34. 125

This movement continues until the parts assume the position indicated in Fig. 4, the edges or fins 65 and 67 bearing on fins 65' and 67' of winged member 37 from the left hand side, the member 37 being moved clockwise to central position and lever 35 being left slightly off center as indicated by the dotted lines in Figure 3. This is of advantage since there will be a tendency on the part of spring-pressed detent 74 to throw the lever 35 to one side as soon as it is drawn away from the locked position of Figure 4, and so to throw in the clutch and start the machine. In this position of parts the reversing clutch will be neutral, the carriage will be stationary and the clutch, 42, 42' will have been thrown in by the yoke 51 connected to lever 35, the spring 56 permitting the clutch member 42' to stop when its end engages that of member 42, and to remain uncoupled until the teeth register. The carriage may now be moved by hand through wheel 50 and its connected parts.

Many variations of structure will occur to those skilled in the art, and my device may be used in different situations and in various arts all without departing from my invention as hereinafter claimed.

In the claims, various specific terms are used, but equivalent devices are in every instance intended to be covered by such terms, which are recited specifically for clearness of description only, and not for limitation.

Having thus fully described my said invention, what I claim as new and desire to secure by Letters Patent, is:

1. In a grinding machine, a driven gear, reversible gearing to drive the same in opposite directions including oppositely rotating devices, a reversing member adapted to engage said devices in alternation, a shifter for said clutch member, a lever adapted to operate the shifter by swinging with the shifter and means adapted to be rendered operative by a different movement of said lever for disconnecting said reversing member, substantially as set forth.

2. In a grinding machine, a driven gear, reversible gearing to drive the same in opposite directions including oppositely rotating devices, a reversing clutch member adapted to engage said gears in alternation, a shifter for said clutch, a lever operatively connected to said shifter and movable in one plane to actuate it to reverse the clutch and also movable in another plane to place it in neutral position, substantially as set forth.

3. In a grinding machine, a driven gear, reversible gearing to drive the same in opposite directions including oppositely rotating gears, a reversing clutch member adapted to engage said gears in alternation, a pivoted shifter for said clutch, a lever pivoted coaxially with the shifter and

adapted to actuate it to reverse the clutch, said lever having a lost motion connection with the shifter, substantially as set forth.

4. In a grinding machine, a driven gear, reversible gearing to drive the same in opposite directions including oppositely rotating gears, a reversing clutch member adapted to engage said gear in alternation, a shifter for the clutch, a lever movable on the same axis as the shifter to operate the same, and also movable on a different axis to place the reversible clutch in inactive position, substantially as set forth.

5. In a grinding machine, a driven gear, reversible gearing to drive the same in opposite directions including oppositely rotating gears, a reversing clutch member adapted to engage said gears in alternation, a shifter for the reversing member, a coaxially pivoted lever having means to move the same, a winged member having engagement with the clutch member to move it to neutral position, and means to operate the winged member, substantially as set forth.

6. In a grinding machine, a driven gear, reversible gearing to drive the same in opposite directions including oppositely rotary driving gears, a reversing clutch member adapted to engage said gears in alternation, a shifter for the reversing member, a coaxially pivoted lever having means to move the same, a winged member having engagement with the clutch member to move it to neutral position, said lever being adapted to operate said winged member, substantially as set forth.

7. In a grinding machine, a driven shaft, a gear thereon, a manually operable shaft adapted to oscillate the first shaft, clutch members on the shafts for connecting them, a live spindle about the manually operable shaft and contracting therewith, and a brake for the corresponding clutch member to hold said manually operable shaft against rotation, substantially as set forth.

8. In a grinding machine, a driven gear, a power shaft to drive the same, a manually operable shaft to drive the gear, a third shaft driven from the power shaft, a live spindle driven by the latter shaft and surrounding the manually operable shaft, and reversing means for the power shaft including a lever and means operated by said live spindle to move said lever in opposite directions to actuate said reversing means, substantially as set forth.

9. In a grinding machine, a driven gear, a power shaft to drive the same, a manually operable shaft to drive the carriage, a third shaft driven from the power shaft, a live spindle driven by the latter shaft and surrounding the manually operable shaft, and reversing means for the power shaft including a reversible clutch member, a lever to actuate the same, a dog wheel having dogs

to move said lever, the dogs being adjustable on the wheel to vary the travel of the carriage and means on the live spindle to drive the dog-wheel, substantially as set forth.

10. In a grinding machine, a driven gear, power-operated means for driving the same comprising a reversible clutch and means for reversing the same, a manually-operable shaft, a clutch on the shaft adapted to clutch the same to the gear driving means, said clutch-reversing means being also adapted to hold the second clutch in inactive relation while the power-operated means is connected to the gear, substantially as set forth.

11. In combination, a driven gear, a manually-operable shaft adapted to drive the same, power operated means adapted to drive the same comprising a swinging lever, a dogging device adapted to swing the lever, and a live spindle about the shaft to operate the dogging device.

12. In combination, a reversible clutch, a lever to operate the same, a dogging wheel to swing the lever in reverse directions, a spindle to drive the dogging wheel, a bearing for the spindle, a shaft adjacent the spindle for driving it, a bearing for the shaft, a face plate holding said wheel in place and means on the bearings for said shaft and said spindle to hold the face-plate in position.

13. In combination, a reversing clutch having a pair of spaced clutch members, a reversing clutch member adapted to engage either of them, a shifter pivoted on an axis extending transversely of the line of movement of the reversing member, and an independently pivoted hand lever connected to the shifter for actuating it by movement in three different directions to cause the clutch member to assume forward, reverse or neutral position respectively, substantially as set forth.

14. In combination, a reversing clutch, a shifter for the reversible member thereof, a member engaging the shifter and having wings with inclined faces, a lever having a pivot in the same plane with those of the shifter and the winged member and having fins at adjacent edges to bear against said wings whereby each of said members is moved toward a central position when the lever is moved into engagement with the winged member.

15. In a grinding machine, a driven gear, reversible gearing to drive the same in opposite directions, including a reversible clutch and means to reverse the same comprising a lever, a dogging device to operate the lever, means on the lever projecting into the path of the dogging device, and adapted to be retracted out of said path, and means to hold said means in retracted position.

16. In a reversible clutch, a shiftable

member, and means for moving the same into neutral position comprising, a shifter on a horizontal pivot, a lever adapted to actuate the shifter by movement on a horizontal pivot, said lever being also pivoted for movement at right angles to the first mentioned movement, an actuator for the clutch shifter mounted on a vertical pivot, and means on the actuator whereby it is moved to central position by the lever in its second named movement, thereby moving the clutch-shifter and rendering the clutch inoperative.

17. In a grinding machine, a driven shaft, a manually-operable shaft adapted to drive said first-named shaft, a bearing concentric with the second shaft, a power shaft extending transversely of the second shaft, a clutch thereon and means pivotally mounted on said bearing for rendering said clutch active or inactive thereby causing the power shaft to drive or release the carriage.

18. In combination, oppositely rotatable clutch members, a reversing member adapted to engage either clutch member, a shifter therefor, a bearing for the shifter, a hub pivoted on the bearing concentrically with the shifter, a lever swingable with the hub and also pivoted to swing on the hub toward and from the clutch, means on the hub to hold it in both positions, and means whereby the lever moves the reversing member to neutral position.

19. In combination, a driven shaft, power driven means to drive the same reversibly, manual means adapted to drive the same reversibly, a lever to control the power driven means, a lever to control the manual means, and a manually operated lever connected to each of the other levers to operate them, substantially as set forth.

20. In combination, a driven shaft, power driven means to drive the same reversibly including a clutch, manual means adapted to drive the shaft reversibly also including a clutch, a hand lever and means connected to the hand-lever to render each clutch active when the other is inactive.

21. In combination, a reversing clutch member, a shifter therefor, a lever adapted to oscillate in either of two parallel planes, means normally connecting the lever to the shifter to reverse the clutch periodically, and means connecting the lever to the shifter at a different point when moving in the second plane whereby the clutch is rendered idle, substantially as set forth.

22. In combination, a reversing clutch member, a lever normally oscillating in a plane to reverse the clutch and connections whereby said lever places the clutch in neutral position when displaced from said plane, substantially as set forth.

23. In combination, a driven member, means for reciprocating said member in-

cluding a reversing clutch, a lever normally oscillating in a fixed plane to reverse said clutch, manual means for actuating said reciprocating member including a clutch, 5 and connections whereby said lever renders the reversing clutch idle and closes the other clutch when displaced from said plane substantially as set forth.

24. In combination, a driven member, 10 means for reciprocating said member including a reversing clutch, a lever normally oscillating in a fixed plane to reverse said clutch, manual means for actuating said reciprocating member including a clutch, 15 a lever movable in a plane at right angles to said fixed plane for shifting said latter clutch, and resilient connections between said levers, whereby movement of the first laterally from said fixed plane closes the 20 second clutch, substantially as set forth.

25. In combination, a driven member means for reciprocating the same including a reversible clutch, a shifter for said clutch, a lever normally oscillating in a fixed plane 25 to reverse said clutch at intervals, manual means for reciprocating said driven member including a clutch, a lever for shifting sail clutch and connections from said first lever to the shifter and to the second lever 30 whereby lateral movement of said first lever closes the last named clutch and renders the reversing clutch idle, substantially as set forth.

26. In a reversing mechanism, a reversing 35 clutch, an oscillating lever for reversing the same periodically, an abutment on the lever, opposed dogs for moving the lever to-and-fro by engagement with said abutment, and means whereby the abutment may 40 be moved on the lever and out of reach of said dogs, substantially as set forth.

27. In combination, a driven member, 45 means for reciprocating the same including a reversible clutch, a shifter for said clutch, a lever normally oscillating in a fixed plane to reverse said clutch at intervals, manual 50 means for reciprocating said driven member including a clutch, a lever for shifting said clutch and connections from said first lever to the shifter and to the second lever whereby lateral movement said first lever closes the last named clutch and renders the reversing clutch idle, an abutment on said 55 first-named lever, opposed dogs engaging said abutment to oscillate the lever, and means for moving said abutment on the lever out of the path of said dogs, substantially as set forth.

28. In a reversing gearing, oppositely rotating driving members, a driven member 60

adapted to engage either driving member, a lever for shifting said driven member, a hub mounted coaxially with said lever, a hand lever pivoted to swing with said hub and also swingable lengthwise of said hub, 65 connections between said levers whereby such lengthwise swinging movement in one direction places the driven member in neutral position and means on the hub for holding the hand lever in the latter position, substantially 70 as set forth.

29. In a reversing gearing, oppositely rotating driving members, a driven member adapted to engage either driving member, a lever for shifting said driven member, a hub 75 mounted coaxially with said lever, a hand lever pivoted to swing with said hub and also swingable lengthwise of said hub, connections between said levers whereby such lengthwise swinging movement in one direction places the driven member in neutral position, a projection on the hub having forwardly and rearwardly inclined faces, and a yieldable detent on the lever having corresponding faces to coact with those on the 80 hub and hold the hand lever in forward or rear position, substantially as set forth.

30. In combination, a reversing clutch having a pair of spaced clutch members, a reversing member adapted to engage either 90 of them, a shifter pivoted on an axis extending transversely of the line of movement of the reversing member, a hand lever pivoted coaxially therewith and also on an axis transverse to that of the shifter and 95 adapted to cause the clutch member by movements about different axis to assume forward, reverse or neutral position, substantially as set forth.

31. In combination, a reversing clutch 100 having a reversely movable clutch member, a movable shifter for said member, an independently movable actuator for the shifter means connecting the shifter and the actuator whereby movement of the actuator in 105 different directions relatively to the shifter may cause said clutch member to assume forward, reverse or neutral position, and means operative at the limit of movement in the respective directions for holding the 110 clutch member in said respective positions, substantially as set forth.

In witness whereof, I have hereunto set my hand and seal at Washington, District of Columbia this thirteenth day of November, A. D. nineteen hundred and twenty.

PAUL STONER. [L. s.]
